UNITED STATES PATENT OFFICE.

ANTONIO PIAZZI, OF GALLARATE, ITALY.

LAMP-HOLDER OF THE EDISON TYPE.

1,362,734.

Specification of Letters Patent. Patented Dec. 21, 1920.

Application filed August 19, 1918, Serial No. 250,578. Renewed November 11, 1920. Serial No. 423,485.

To all whom it may concern:

Be it known that I, ANTONIO PIAZZI, residing at Via Como, Casa Trolli, Gallarate, in the Kingdom of Italy, have invented new 5 and useful Improvements in Lamp-Holders of the Edison Type, of which the following is a specification.

The object of the present invention is a lamp-holder of the Edison type which is 10 made of insulating material and in two parts so that it can be readily taken apart, and it serves at the same time as a switch; a considerable saving of material is therewith obtained and it can be touched without any 15 danger.

The annexed drawing represents two embodiments of the invention by way of example.

Figure 1 is an external view of the lamp-holder in working order.

Fig. 2 is a section thereof to a larger scale.

Fig. 3 shows lamp-holder in plan as seen from the inside of the base-piece.

Fig. 4 is a section showing a modified construction.

The holder comprises two parts made of insulating material such as fiber, ebonite, porcelain or the like, one part being screwed 30 into the other, viz., the base-piece —a— and the socket —b—. The base-piece —a— is fitted with a suspension ring —c— and an inside projection —a'— increasing the thickness of the base-piece and provided 35 with a center hole —d— for passage of one of the leads. The inner end of this lead is clamped inside a metal block —e—, whose 40 springing shank enables the block to be firmly held in the bell-mouthed inner end of passage —d—.

In the base-piece —a— an eccentric hole —f— is also formed for passage of the second lead, this hole too being provided with a clamping block —g— fitted with springing shank; the block —g— is lodged higher 45 up in the base-piece —a— than block —e—.

The socket or sleeve —b— is screw-threaded externally for connection to the

base-piece, and internally for receiving the lamp; both the internal screw-threaded surface and the external screw-threaded portion in touch with the base-piece —a— are lined, galvanically or otherwise, with a metal plating —i—, say of copper.

The metal cap of the lamp makes contact 55 with the metal plating —i—, which in its turn is electrically connected to the eccentric block —g—. The center contact of the lamp butts against the center block —e— and in this way the lamp filament can be connected 60 to both lead-wires. To interrupt the connection it suffices to slacken the screw-connection between —a— and —b—.

In the modified construction according to Fig. 4 the eccentric hole —f— is replaced by 65 a radial hole —f'— formed in the side of the projection —a'—, so that also the second wire can be led through the center hole —d— and thence, through the side hole —f'—, to the eccentric block —g—.

Having now fully described my invention what I claim is:

A lamp-holder of the character described comprising a base piece and a socket of insulating material and capable of being 75 screw-threaded into one another, a central inwardly projecting portion on the base piece, the base piece being provided with a central hole and with an eccentric hole, each of said holes being adapted to be traversed 80 by one of two lead wires, metal blocks each of which are provided with a central opening and with an elastic-slit shank, the shanks of the blocks being tightly fixed in the center and eccentric holes and designed to 85 firmly grip the ends of the respective wires, one of said blocks being adapted to make contact with the center contact of a lamp and a metal plating on the internal head surface and on the internal screw-threaded 90 surface of the socket adapted to make contact with the other block in order to establish an electric contact between said block and the metal cap of a lamp.

In testimony whereof I affix my signature. 95
ANTONIO PIAZZI.
